VAPORIZER

Filed March 16, 1928

Inventor:
Hans Münter,
by *Charles E. Yuller*
His Attorney.

UNITED STATES PATENT OFFICE

HANS MÜNTER, OF HENNIGSDORF, GERMANY, ASSIGNOR TO GENERAL ELECTRIC COMPANY, A CORPORATION OF NEW YORK

VAPORIZER

Application filed March 16, 1928, Serial No. 262,250, and in Germany November 9, 1926.

My invention relates to that class of welding wherein gaseous media are used to improve the physical characteristics of the weld metal. More particularly, my invention relates to apparatus for producing the desired gaseous media from normally liquid substances. Among various substances, recently called to the public's attention, which when heated will supply a suitable vapor in 10 which to conduct a welding operation are the alcohols, especially methanol. This last substance which has a chemical formula of CH_3OH will yield when decomposed carbon monoxide and hydrogen in which it is possible to produce welds of superior quality.

An object of my invention is to produce an improved vaporizer by means of which a liquid, such as methanol, may be safely vaporized and supplied to the welding zone at 20 a uniform pressure.

A further object of my invention is to provide a vaporizer in which the vapor is first generated and then superheated or reheated in order to prevent particles of liquid reaching the point of welding.

A further object of my invention is to so construct the vaporizer that condensation of the generated vapor is prevented during its passage to the superheater above referred to.

In order to secure a safe operation of the vaporizer it is desirable that the level of the liquid therein shall not exceed a certain maximum so that a sufficiently large space for the accumulation of vapor be provided therein.

A further object of my invention is to provide means for filling the vaporizer to a predetermined extent without depending on gauge glasses, drawing-off taps, or the like.

Further objects of my invention will be better understood from the following description taken in connection with the accompanying drawing and the scope of my invention will be pointed out in the appended claims.

The single figure of the drawing illustrates a side view partially in section of an evaporator embodying the several features of my invention.

Referring to the vaporizer shown in the drawing, a closed bottle or container 1 in

which is placed the substance to be evaporated 2 is maintained at a substantially constant temperature by being immersed in a liquid bath 3 within a tank or boiler 4 which is heated by suitable heating means illustrated as 55 an electric heater 5. If the substance to be vaporized is methanol and the liquid bath 3 is water, the arrangement described will function to deliver methanol vapor at 3.5 atmospheres since the boiling point of water is 60 100° C. at normal pressure and at this temperature the vapor pressure of methanol is 3.5 atmospheres. The vapor generated within the bottle 1 is conducted through a passageway 6 in a plug 7 closing the neck 8 of 65 the bottle, thence through a pipe 9, a valve 10, and a second pipe 11 to the superheater 13 immediately associated with the heating means 5. As shown this superheater is made of a bent copper pipe located adjacent the 70 heating means 5. By enclosing within the tank or boiler 4 the connections between the bottle 1 and the superheater 13 condensation in these connections of the vapor generated in bottle 1 is prevented. Within the super- 75 heater 13 the temperature of the vapor is sufficiently raised so that there is little tendency for the vapor to recondense before reaching the point of its application through a tube (not shown) connected at 14 to the 80 superheater 13.

Bottle 1 may be filled by closing valve 10 through the agency of its handwheel 15 which extends outside the boiler 4 and by opening the normally closed valve 16 which opens a 85 passageway from without the boiler 4 into the container 1, through funnel 17, pipe 18, valve 16, and pipe 19. The pipe 19 extends into the bottle and has its terminal located a predetermined distance from the top of the 90 bottle so that upon filling the bottle the air cushion located above the terminal of this pipe prevents more than a certain amount of liquid being placed in the bottle. That is, upon filling the bottle with liquid a certain amount of air and vapor in the bottle 95 is unable to escape from the bottle through valve 10 which is closed or through the pipe 19 by reason of the liquid already in the bottle. Therefore, the liquid in the pipe 19 rises and 100

eventually reaches the funnel 17 which notifies the operator that the bottle is filled to its predetermined level. If thereafter the operator opens valve 15 and allows the air 5 imprisoned in the upper part of the bottle 1 to escape the liquid in funnel 17 and pipes 18 and 19 will flow into the bottle but will be insufficient to fill the bottle, thus leaving a certain space at the top of the bottle for 10 the accumulation of vapor during the initial period of operation of the evaporator. In this manner the level of the liquid in the bottle is readily adjusted to a predetermined height without making use of gauge glasses, 15 drawing-off taps, or the like.

It is desirable to choose the dimensions of the bottle so that it will function for a sufficiently long period of time to satisfy the normal requirements for which it is built. 20 Thus if the evaporator is used in welding it is desirable to construct the bottle 1 for a capacity of about 3 liters which will be sufficient to supply to the usual welding nozzle the desire amount of gas for an 8-hour operating period. If refilling is nevertheless necessary the water 3 in the boiler 4 may be drawn off for the most part through a tap 20 and cold water poured in through an opening in the top of the boiler 4 which is normally 30 closed by a cover. A baffle plate 21 is provided within the boiler 4 for preventing this cold water from striking the hot bottle. As soon as the temperature of the water in the boiler 4 has fallen below 66° C. the boiling 35 point of methanol at normal pressure, the bottle may be opened and fresh methanol supplied in the manner previously described.

It is, of course, apparent that evaporators may be employed in accordance with the disclosure for the evaporation of liquids other than methanol while using heat transmission media other than water at temperatures other than 100° C. It is also apparent that the heating means may be non-electrical. In 45 other words, the proposed arrangement may be modified to meet varying requirements without departing from my invention which has been shown and described in connection with a simplified arrangement for the purpose of clearly illustrating the invention, and I, therefore, aim in the appended claims to cover all such changes and modifications as fall within the true spirit and scope of my invention.

50 What I claim as new and desire to secure by Letters Patent of the United States is:

1. In combination, a closed container having a discharge passageway in its top portion, a liquid bath in which said container is 55 immersed, means for heating said liquid bath, means associated with said heating means for heating vapor after it has been discharged from said container and a pipe connected to said discharge passageway and to said last- 60 mentioned means.

2. In combination, a closed container, means for maintaining said container at an approximately constant temperature, means for superheating the vapor supplied from said container, and means for maintaining the vapor discharged from said container at an approximately constant temperature equal to that of said container until said vapor is delivered to said superheating means. 70

3. In combination, a closed container, a 75 boiler within which said container is enclosed, means for heating said boiler, means associated with said heating means for superheating a vapor generated in said container, and means totally enclosed within said boiler for 80 connecting said container with said superheating means.

4. A totally closed container, a discharge conduit connected to said container, means for filling said container to a predetermined 85 level including a pipe inserted into the container and having its discharge terminal located a predetermined distance from the top of said container, and valve means in said conduit and in said pipe. 90

5. A totally closed container, a boiler within which said container is located, means for withdrawing liquid from said boiler and means for supplying liquid to said boiler, said last mentioned means including a baffle located within said boiler for preventing newly supplied liquid from impinging directly on said container. 95

In witness whereof, I have hereunto set my hand this 24th day of February, 1928. 100

HANS MÜNTER.
